[57] CLAIM

The ornamental design for crowd and field scene wallpaper, as shown and described.

DESCRIPTION

The sole FIGURE is a top plan view of a single repeat of the wallpaper design according to my new design. The drawing is lined to represent color, with the dual red stripes separated by a white stripe representing the hoarding section, the green lower portion representing the sward, and the crowd being represented thereabove.

The wallpaper has no substantial thickness. The rear surface forms no part of the claimed design. The broken line top and bottom boundaries in the drawing indicate that the wallpaper continues indeterminately up and down and that the pattern repeats uniformly in both directions.
